UNITED STATES PATENT OFFICE.

ARTHUR STEWART, OF PHILADELPHIA, ASSIGNOR OF ONE-HALF TO
WILLIAM H. MATTSON, OF SHARON HILL, PENNSYLVANIA.

PADLOCK.

SPECIFICATION forming part of Letters Patent No. 247,963, dated October 4, 1881.

Application filed August 8, 1881. (No model.)

To all whom it may concern:

Be it known that I, ARTHUR STEWART, a citizen of the United States, residing in Philadelphia, Pennsylvania, have invented an Improvement in Locks, of which the following is a specification.

The object of my invention is to provide for railway cars, switches, and for other uses a lock which shall have all the appearance of an inexpensive iron lock, but which shall be as free, so far as the operating parts are concerned, from the detrimental effects of exposure as a lock made wholly of brass. This object I attain in the manner which I will now proceed to describe, reference being had to the accompanying drawings, in which—

Figure 1 is a perspective view, showing the outer case and shackle of the padlock; Fig. 2, a view of the cover of the case; and Fig. 3, a perspective view of the interior plate, with tumblers and other operating parts carried by the said plate.

A is the iron case of the lock, and B the cover, adapted to the rim *a* of the said case, to which the cover is to be riveted in the usual manner.

D is the shackle, having at one end a brass bushing, D', adapted to a pivot-pin, *d*, on the case, the slotted free end *b* of the said shackle being arranged to pass through an opening, *e*, in the rim of the case.

The above description will apply to an ordinary padlock, which has been selected for the illustration of my improvement, for it should be understood that my invention may be applied to any style of lock which will permit the introduction into an outer case of cast-iron of the plate G, of brass or any non-corrosive metal or alloy. This plate is made to fit snugly within the rim of the iron case, and is confined to the same by the cover B, so that when the plate is contained in the case it becomes essentially a fixed portion of the same, the operating parts of the lock being carried by the plate instead of being applied directly to the cast-iron case, as in ordinary locks. The plate G may be riveted to the outer case at one or more points, if desired.

My invention does not demand any specific kind of works or operating parts; but it is essential that these parts, or at least the greater portion of them, should be non-corrosive and carried by the plate of non-corrosive metal or alloy. The works consist, in the present in-

stance, of the sliding spring-bolt H, tumblers I, and hook J, the construction and operation 55 of which for retaining and releasing the slotted end of the shackle will be readily understood by those familiar with the construction of locks. The plate G also carries the stem *h* and guide *i* for the key, as well as the spring for the bolt. 60

My invention may be applied with advantage to all locks which are so exposed as to be liable to become rusted and their works inoperative, and it is especially applicable to padlocks used on railway cars or switches, for ordinary 65 locks for this purpose are often made with cases of brass, which offer temptations to a class of thieves who are in the habit of stealing such locks, the losses of railroad companies through such purloining being very serious. 70

My improved lock has externally the appearance of a common iron lock, and therefore is not a tempting looking affair in the eyes of thieves. At the same time, the operating parts being non-corrosive and carried by a non-cor- 75 rosive plate, they are not liable to become inoperative through accumulations of rust.

As a further provision against the detrimental effects of exposure, I prefer to line the iron cover B with a plate, *f*, of non-corrosive metal 80 or alloy; or the inner face of the plate may be galvanized or otherwise coated, so as to resist the attacks of moisture.

It may not be necessary in some styles of locks that all the works should be non-corrosive or carried by the non-corrosive plate; but it is important that the bolts, tumblers, and other movable parts should be of non-corrosive metal and should have bearings on the plate G, or on projections on the same, so 90 that they will not be detrimentally affected by moisture.

I claim as my invention—

A lock in which an outer case of iron is combined with a non-corrosive plate fitted to the 95 said case, and carrying the works of the lock, or the greater portion thereof, substantially as described.

In testimony whereof I have signed my name to this specification in the presence of two sub- 100 scribing witnesses.

ARTHUR STEWART.
